UNITED STATES PATENT OFFICE.

ERNEST KARL, OF LITCHFIELD, CONNECTICUT.

TYMPAN-GAGE.

1,170,274.

Specification of Letters Patent.

Patented Feb. 1, 1916.

Application filed May 19, 1915. Serial No. 29,142.

To all whom it may concern:

Be it known that I, ERNEST KARL, a citizen of the United States, residing at Litchfield, in the county of Litchfield and State 5 of Connecticut, have invented a new and useful Tympan-Gage, of which the following is a specification.

The present invention appertains to tympan gages for printing presses, and aims 10 to provide a novel and improved appliance adapted to be employed upon the platen of a printing press for properly holding the sheets whereby they receive the impressions regularly.

15 It is the object of the invention to provide a tympan gage which is adjustable to hold various sizes of sheets, and to hold the sheets at various positions upon the platen, the device being comparatively simple, practical and inexpensive in construction, being 20 readily applicable to various printing presses, and serving its office in a thoroughly efficient, convenient and practical manner.

25 With the foregoing and other objects in view which will appear as the description proceeds, the invention resides in the combination and arrangement of parts and in the details of construction hereinafter described and claimed, it being understood 30 that changes in the precise embodiment of the invention herein disclosed can be made within the scope of what is claimed without departing from the spirit of the invention.

35 The invention is illustrated in the accompanying drawings, wherein:—

Figure 1 is a plan view of a printing press platen with the improved appliance applied thereto. Fig. 2 is an enlarged sectional detail illustrating the gage strip bent upwardly to one side off of the platen, portions of the strip being broken away. Fig. 3 is an enlarged edge view of the platen illustrating the gage device, portions being broken away. Fig. 4 is an enlarged plan view of the gage strip, the intermediate portion thereof being broken away. Fig. 5 is an enlarged plan view of the blank 45 from which one stop or lower gage is fashioned. Fig. 6 is an enlarged plan view of the blank from which the slide of the side gage is formed. Fig. 7 is an enlarged plan view of the blank from which the side gage 50 is formed, a portion thereof being broken away. Fig. 8 is an enlarged sectional de-

tail taken through one of the stops and the gage strip. Fig. 9 is an enlarged sectional view taken through the slide of the side gage and the gage strip.

In carrying out the invention, there are attached to the side edges of the platen 1, a pair of opposite parallel angle iron guides 2, having upper outwardly projecting flanges provided with longitudinal slots 2^a, and having inwardly disposed depending flanges. The downwardly projecting flanges of the guides 2 are each provided with a pair of T-shaped slots 3, and a pair of bolts 4 are engaged to each side edge of the platen 1, and are received by the T-shaped slots 3. A nut 5 is threaded upon each bolt 4, for clamping the depending flanges of the guides 2 to the side edges of the platen. When the nuts 5 are loosened, the guides 2 may be shifted longitudinally of themselves, or may be removed from the platen, as will be evident. Since the remainder of the gage device is carried by the guides 2, the guides 2 in being removed from the platen, will remove the entire gage device from the platen, and when the guides 2 are adjusted, the entire gage device is adjusted relative to the platen.

A bolt 6 is slidable in each slot 2^a and has an upper wing or thumb nut 7 threaded thereon, the heads of the bolts 5 being disposed under the upper flanges of the guides 2. A gage strip 8 extends across the platen 1 and has its end portions resting upon the guides 2, the strip 8 being provided adjacent one end with a transverse slot 9 which is engageable with one of the bolts 6, and the other end of the strip 8 has a longitudinal open slot 10 for receiving the other bolt 6. The strip 8 is adapted to rest upon the platen 1 when both ends of the strip are fastened to the guides. The strip 8 has a tendency to curl or bend upwardly to one side of the platen, as illustrated in Fig. 2, or the strip 8 has a normal tension tending to bend the strip into circular or loop form, whereby when the ends of the strip are engaged to the bolts 6, the strip will bear upon the platen firmly. The strip 8 is provided with lower longitudinal rabbets 8^a along its side edges, and extending from end to end.

A pair of stops or lower gages 11 are slidably mounted upon the strip 8, and a side gage 12 is also similarly adjustable upon the gage strip. Each of the stops 11 is bent from a blank of sheet metal, and comprises

a body 13 resting slidably upon the strip 8, and having a lip 14 at one end bent back or reflexed under one edge of the strip 8 while the other end of the body 13 has a pair of lips 15 which are bent back or reflexed under the other edge of the strip 8 to grip the strip and hold the stop in position. The lips 14 and 15 are received by the rabbets 8^a of the strip 8, whereby the stops 11 will not 10 project below the lower surface of the strip, which would be objectionable. The side edges of the body 13 are provided with notches 16, forming flanges 17, and the flanges 17 are bent upward, to provide finger pieces which may be readily grasped by the fingers for shifting the stop along the gage strip. The body 13 has a tongue 18 projecting from between the lips 15, at the respective end of the body 13, and the 20 tongue 18 is bent back over the body 13, and is bowed, as seen in Fig. 8. The tongue 18 has a head or enlarged portion 19 at its free end, which is bent upwardly, and the head 19 has a pair of feet 20 at the opposite 25 sides of the tongue 18, which are adapted to rest upon the platen 1. The head 19 has a lip 21 at its upper edge, which is bent angularly away from the tongue 18, whereby the lip 21 overhangs the edge of the sheet, 30 while the edge of the sheet rests against the feet or stops 20. The side gage 12 is carried by a slide which is mounted for movement upon the strip 8, and this slide is bent from a sheet metal blank, and embodies a body 22 resting slidably upon the strip 8, and having a pair of lips 23 at each 35 end, and the lips 23 are bent back or reflexed under the edges of the strip 8, and are received by the rabbets 8^a of the strip. 40 The body 22 has a portion 24 projecting from each end between the respective lips 23, and each portion 24 has lips 25 at its side edges bent back upwardly. The body 22 has a pair of notches 26 at each side 45 edge, and the notches 26 form flanges 27 which are bent upward to provide finger pieces whereby the slide may be readily moved upon the strip 8.

The side gage proper embodies a strip 28, 50 cut from sheet metal, and having a portion 29 at one end curved to one side, and the curved end portion 29 of the strip 28 is provided with a head or enlarged portion 30 which is bent upward. The head or portion 55 30 is provided with a pair of feet 31 at the opposite sides of the end portion 29 of the strip 28, and the feet 31 are adapted to rest upon the platen 1. The head 30 has a lip 32 at its upper edge which is bent angularly 60 relative to the head 30, to overhang the edge of the sheet, while the edge of the sheet rests against the teeth or stops 31.

In use, when the device is properly applied to the platen, the stops 11 may be adjusted along the strip 8 as well as the side

gage 12, whereby the stops and side gage will properly hold the sheet to be printed upon and the strip 8 may be adjusted upwardly and downwardly upon the platen 1. Thus, when the nuts 7 are loosened, the bolts 6 are free to slide in the slots 2^a of the guides and the strip 8 may be adjusted to the position desired. It is thus possible to adjust the device for holding various sizes of sheets, and for holding the sheets at various 75 positions upon the platen. The sheet rests against the feet 20 and 31 of the stops and side gage, respectively, under the lips 21 and 32. It is also to be noted that the strip or shank 28 of the gage 12 may be slid relative 80 to the slide, since this strip 28 rests slidably upon the body 22 and portion 24 of the slide, under the lips 25.

Attention is directed to the fact, that the open longitudinal slot 10 in one end of the strip 8 allows the said end of the strip to be moved by longitudinal movement into engagement with the right hand bolt 6, while the lateral slot 9 at the other end of the strip 8 allows the last mentioned end of the strip to be moved by a lateral or swinging motion into and out of engagement with the left hand bolt 6. The slot 10 allows the bolts 6 to be spaced farther or less apart, since the right hand bolt 6 may be disposed at any 95 point within the slot 10, without disturbing the position of the strip 8 when it is clamped to the guides.

The other advantages and attributes of the invention are thought to be obvious from 100 the foregoing, taken in connection with the drawing, without further comment being necessary.

Having thus described the invention, what is claimed as new is:

1. In a device of the character described, a pair of angle iron guides applicable to the side edges of a platen, the guides having depending flanges provided with T-shaped slots for the reception of securing elements carried by the side edges of the platen, the other flanges of the guides having longitudinal slots, elements slidable in the last mentioned slots, a strip engageable with said elements to extend across the platen, and gage elements slidable upon the strip.

2. In a device of the character described, a pair of guides applicable to the side edges of a printing press platen, a pair of adjustable clamping elements carried by the guides, a strip adapted to extend across the platen and having a longitudinal open slot at one end for the reception of one clamping element, and a transverse slot adjacent its other end for the reception of the other clamping element, and gage elements slidably mounted upon the strip.

3. In a device of the character described, a strip adapted to extend across a printing press platen and having lower longitudinal

rabbets along its edges, a slide embodying a body resting upon the strip and having a pair of lips at each end bent back under the respective edge of the strip and received 5 by the corresponding rabbet, said body having portions projecting from between the lips, and said portions having lips bent back upwardly from its side edges, and a side gage strip slideable upon the slide and 10 said portions thereof under the last men-

tioned lips, the last mentioned strip having means at one end to bear upon the platen for the engagement of a sheet therewith.

In testimony that I claim the foregoing as my own, I have hereto affixed my signature 15 in the presence of two witnesses.

ERNEST KARL.
